(57) **CLAIM**

The ornamental design for a food sealed storage bag, as shown and described.

DESCRIPTION

FIG. 1 is a front elevational view of a food sealed storage bag showing my new design;

FIG. 2 is a rear elevational view thereof; and

FIG. 3 is a left elevational view thereof;

FIG. 4 is a right side view thereof;

FIG. 5 is a top side view thereof;

FIG. 6 is a bottom plan view thereof;

FIG. 7 is a perspective view of a food sealed storage bag showing my new design;

FIG. 8 is another perspective view thereof; and,

FIG. 9 is a perspective view showing that the food sealed storage bag is open.
